FLUID CONTAINER

Joseph W. Patterson, Tulsa, Okla.

Application October 21, 1940, Serial No. 362,070

4 Claims. (Cl. 220—27)

This invention relates to new and useful improvements in fluid containers.

One object of the invention is to provide an improved container which is so constructed that a dispenser may be readily connected thereto, whereby the container may be marketed separately of and apart from the dispenser.

An important object of the invention is to provide an improved fluid container which is tamper-proof and which may be attached to the conventional fluid sprayer barrel, or other dispensing apparatus, whereby the container in which the fluid is sold may be utilized as the fluid container of the sprayer or other dispensing apparatus.

Another object of the invention is to provide an improved container, of the character described, wherein the means for connecting the dispenser to the container is disposed within the body of said container, whereby the exterior of the container is substantially smooth and also whereby said container may be filled and sealed with the automatic equipment in general use at the present time.

A particular object of the invention is to provide an improved container having an opening which is normally sealed by a frangible closure so that the container reaches the consumer in a sealed condition, the frangible closure being arranged to be ruptured when the dispenser is connected therewith so as to permit access to the contents of said container; the container being preferably constructed of a relatively inexpensive material so that it may be discarded after its contents are consumed and a new, full container substituted for the same, thereby obviating the necessity of employing a single receptacle with the dispenser and refilling such receptacle from time to time.

A further object of the invention is to provide an improved non-refillable container having a positive seal at the point of its connection with a dispenser, whereby the container may only be used until emptied so as to assure a new seal which substantially eliminates leakage.

Still another object of the invention is to provide a fluid container, of the character described, wherein the contour of the container is utilized to co-operate with the connecting means between the dispenser and container so as to assure a tight connection therebetween.

A still further object of the invention is to provide an improved container wherein the sealing means is so arranged that any pressure within the container, when the container is attached

to the dispenser, will tend to increase the seal between the parts to prevent any leakage at the point of attachment.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an isometric view of an improved container, constructed in accordance with the invention.

Figure 2 is a plan view of the container.

Figure 3 is an enlarged, transverse, vertical, sectional view of the upper portion of the container and illustrating the connecting means.

Figure 4 is a view, partly in section and partly in elevation, showing the container connected to the barrel of a sprayer.

Figure 5 is a view, similar to Figure 3, of a slightly modified form of container.

Figure 6 is a view, similar to Figures 3 and 5, of still another form of the invention.

Figure 7 is a plan view of another form.

Figure 8 is an enlarged, transverse, vertical, sectional view of this form.

Figure 9 is a view, similar to Figure 4, of the same, and

Figure 10 is a view, similar to Figure 8, of still another form of container.

This application is filed as a continuation-in-part of my co-pending application Serial No. 316,311, filed January 30, 1940.

In the drawings, the numeral 10 designates cylindrical container, can or receptacle which is constructed of tin, or other suitable material. The container is made in the usual manner and includes a cylindrical wall 11 which is formed of one piece of material and which has circular end plates or disks 12 crimped, or otherwise secured thereto, as shown in Figure 2. The container may be of any desired shape so as to have the desired fluid content. An opening 13 is formed in the wall 11 of the container, being preferably disposed centrally with respect to the end walls 12 and being substantially circular in shape. A pair of diametrically opposed recesses 14 which are substantially semi-circular in shape, are provided at the marginal portion of the opening, and these recesses are disposed in a plane parallel to the longitudinal axis of the container. Obviously, since the opening 13 and recesses 14 are formed in the curved wall of the container, said opening

and recesses are curved, relative to a horizontal plane, as is clearly shown in Figure 3. However, since the recesses are disposed in alignment with the longitudinal axis of the container, and being of a narrower width than the circular opening, said recesses do not have as much curvature transversely thereof as does the opening. Due to the size of the openings, the transverse or lateral portions 15 of the opening, which are located in a plane at a right angle to the longitudinal axis of the container are disposed below the central portion of the openings in a horizontal plane as shown in Figure 3.

A cylindrical body or member 16 which has the form of an inverted cap, is located within the container below the opening 13, and this member includes a base plate, or bottom 17, provided with its upstanding angular flange 18. The upper end of the flange 18 is soldered, or otherwise secured, to the inside wall of the container immediately beneath said opening and the diameter of said member is sufficient to encircle the recesses 14, as well as the opening (Figure 4). The bottom 17 of the member is provided with an axial opening 19 which is normally sealed by a frangible closure disk 20. Since the bottom of the member 16 is spaced from the opening 13, and also from the inner wall of the container, an internal chamber A is formed below the opening. An annular sealing gasket, or ring 21, may be placed within this chamber, said gasket being positioned within the member 16 prior to its attachment to the container. However, in some instances, the gasket may not be necessary and may be omitted.

The member 16, as well as the opening 13 and recesses 14, are utilized to connect the container, or can 10 to a sprayer barrel, or other dispensing apparatus, as will be hereinafter fully explained. It is pointed out that the member 16 is disposed within the container and takes up a relatively small amount of the internal area thereof, whereby it does not materially reduce the fluid content of said container. By disposing the member within the interior of the container, the outer surface thereof remains smooth and no projections are formed on such surface. Therefore, the container has an exterior construction which is exactly the same as the usual containers or cans which are now in general use for marketing motor oils, canned foods, and similar products, and such containers may be filled and sealed with the present kind of automatic jelly and sealing equipment which is now in use. It is specifically noted that no expensive or special equipment is required. The container may be filled with an insecticide or other fluid to be sprayed or dispensed.

The particular type of container, or can, illustrated is adapted to be connected to the depending collar 22 of a sprayer barrel (not shown) which also includes a depending eduction tube 23. As is clearly shown in Figure 4, the lower end of the tube projects a substantial distance below the collar 22. The diameter of the collar is substantially equal to the diameter of the circular opening 13 formed in the wall of the container 10, whereby this collar is insertable therein. A pair of diametrically opposed radially extending lugs 24 are preferably formed integral with the collar, and said lugs extend in a plane parallel to the longitudinal axis of the sprayer barrel (not shown).

In attaching the sprayer barrel to the container, or can, the frangible closure disk 20 mounted in the bottom of the member 16, is punctured, or ruptured, by any suitable means, it being possible

to employ the lower end of the eduction tube 23 for this purpose. The tube is then introduced through the punctured disk and is lowered until the collar 22 enters the opening 13 in the wall 11 of the container. The collar 22 is then rotated to align the radial lug 24 with the recesses 14 which are located at the marginal portion of the opening 13. Due to the disposition of these recesses, as well as the location of the lugs 24, it is necessary to align the longitudinal axis of the container with the longitudinal axis of the barrel (not shown) in order to bring the lugs into registration with the recesses. After the lugs are aligned with the recesses, further downward movement of the collar 22 may continue until the lower end thereof strikes the gasket 21 within the chamber A. At this time, the upper surfaces of the lugs 24 are within the chamber immediately below the inner wall thereof. Upon rotation of the collar 22, the lugs 24 are moved out of alignment with the recesses 14 and are engaged with the inner wall of the container beneath the marginal portion surrounding the circular opening 13, as is clearly shown in Figure 4. Due to the curved inner surface of the container co-acting with the straight lugs 24, a cam action is had which serves to draw the collar 22 into a tight engagement with the packing gasket 21. Also, a tight frictional engagement between the lugs and container is set up, whereby the connection between these elements is positively maintained.

It is manifest that when the container and the collar of a sprayer barrel are connected, as above described, a complete sprayer is had and that any drainage of fluid from the barrel will pass downwardly through the collar and then back into said container. It is noted that any pressure present, or which is built up in the container will act against the underside of the bottom 17 of the member 16 so as to urge said member upwardly and force the gasket 21 against the lower end of the collar 22, thereby assuring a fluid-tight seal between said collar and gasket. When the container is empty, it is discarded and a new one is substituted therefor. By providing this type of container, a liquid insecticide, or other fluid, may be sealed in a container which is temper-proof, so as to be in the same condition when offered for sale to the consumer. After purchase, the consumer may readily attach the container to the collar of a sprayer barrel, or other dispenser, and dispense the contents as desired. Thus, the same container which is employed for selling the fluid is utilized as a receptacle for the sprayer or dispenser.

Since each container has a sealing gasket incorporated therein, it is manifest that each time a container is emptied, and a new one substituted therefor, a new seal is provided. This arrangement assures a fluid-tight seal at the point of connection at all times.

In Figure 5, a slightly modified form of the container is shown, and this container has a circular opening 25 formed in the wall thereof, such opening being substituted for the opening 13 and recesses 14 of the first form. A hollow element 26 is substituted for the member 16 and this element is constructed of an outer flange member 27 which is insertable within the opening 25, being soldered or otherwise secured therein. The member 27 is comparable to the member 16, being provided with an axial opening 28 which is closed by a frangible disk 29. The gasket 21 is supported within the member and a flange cap 30 is also insertable within the member. The top of the

cap 30 is arced or curved so as to form a continuation of the curved surface of the container. The circular opening 13 and recesses 14 are provided in the curved top of the cap 30, and, manifestly, the collar 22 of the sprayer barrel or other dispenser may be readily connected thereto in the manner hereinbefore described.

Another form of the invention is shown in Figure 6 and includes a flange cap 31 which is secured in the opening 25. The top of the cap 31 is curved and is provided with the opening 13 and recesses 14, whereby said cap top forms a continuation of the wall 11 and, in effect, a part thereof. The flange 32 of the cap depends into the interior of the container and has a circular base plate 33 extending across the lower portion thereof. The base plate has an axial opening 34 and this opening is normally closed by a frangible plate, or disk, 35 which overlies the plate 33. To simplify manufacturing costs, the marginal edges of the plates 33 and 35, as well as the ends of the flange 32, are crimped together. Of course, these points may be secured in any other suitable manner. Since the plate 35 is constructed of frangible material, such as lead or the like, it is not necessary that a sealing gasket be employed in this form. However, if desired, the gasket 21 may be used. Manifestly, the operation of this modification is the same as the other forms of the invention hereinbefore described.

In some instances, it might be desirable to construct a container in the manner shown in Figures 7 to 9. In this event, the wall of the container 10 is provided with an oval shaped opening 36 which is normally sealed by a frangible disk 37 secured to the inner wall of the container beneath the opening. The sprayer barrel (not shown), or other dispensing apparatus, is provided with a depending collar 38 having lugs 39 thereon, and said lugs and collar are insertable through the opening 36, as will be readily understood. An annular flange 40 is formed on the collar above the lugs and, when said lugs are rotated to engage the underside of the container as shown in Figure 9, the flange is spaced from the outer surface of said container. A suitable packing gasket 41 surrounds the collar 38 and is clamped between the outer surface of the container and the flange 40 so as to seal the opening 36. It is obvious that this is a relatively simple form of the invention and is preferably employed with sprayers and other dispensers which are not

of the pressure type. However, it might be possible to clamp the gasket 41 sufficiently tight beneath the flange 40 to resist a leakage of pressure within the container. If desired, the frangible disk 37 which seals the opening 36 may be secured to the external surface of the wall 11 of the container as shown in Figure 10. It is pointed out that the openings of the containers which have been described hereinbefore may be formed in the circular end plates 12 of said container.

The foregoing description of the invention is explanatory thereof and various changes in the size, shape, and materials, as well as in the details of the illustrated construction may be made, within the scope of the appended claims, without departing from the spirit of the invention.

What I claim and desire to secure by Letters Patent is:

1. A dispensing container including, a container body having an opening in one of its walls, and a hollow member insertable within the opening and adapted to be fastened therein with its top substantially flush with the outer surface of the container, the bottom of the member having a frangibly-sealed outlet opening therein, the top of said member having an opening therein of a configuration to pass the fastening means of an element therethrough, whereby the container may be connected to the element by engagement 30 of said fastening means with the internal surface of the member contiguous to the opening thereof.
2. A container as set forth in claim 1, wherein a frangible disk normally seals the outlet opening formed in the bottom of the hollow member 35 and the opening in the top of said member is substantially in the form of a slot.
3. A container including, a container body having an opening in one of its walls, a hollow member insertable within the opening and adapted to 40 be fastened to the container with its top in said opening and substantially flush with the exterior surface of said container, the hollow member including a cap and a base plate having an opening therein, the cap and base plate being secured 45 together to form a unit, the top of said cap having a slot therein for receiving the fastening means of an element, and a frangible plate closing the opening of said base plate.
4. A container as set forth in claim 3 wherein 50 the frangible plate is secured to the cap and base plate of the hollow member.

JOSEPH W. PATTERSON.
